ELECTRODE HOLDER

Frank Malner, Cleveland, Ohio, assignor to The Lincoln Electric Company, Cleveland, Ohio, a corporation of Ohio

Application May 16, 1932. Serial No. 611,487

1 Claim. (Cl. 219—8)

This invention relates as indicated to electrode holders and has more specific reference to the form of construction of a tool for manipulating the pencil employed in arc welding processes.

It is an object of this invention to provide a form of construction of electrode holder in which the insertion of the pencil into the holder is greatly facilitated. It is a further object of my invention to provide a holder construction which shall be extremely light and accordingly easy to manipulate and which also may be made at a very low cost. Other objects of my invention will appear as the description proceeds.

To the accomplishment of the foregoing and related ends, said invention, then consists of the means hereinafter fully described and particularly pointed out in the claim.

The annexed drawing and the following description set forth in detail certain mechanism embodying the invention, such disclosed means constituting, however, but one of various mechanical forms in which the principle of the invention may be used.

In said annexed drawing:

Fig. 1 is a perspective view of one form of holder constructed in accordance with the principles of my invention; Fig. 2 is a longitudinal sectional view of the holder illustrated in Figure 1; Fig. 3 is a transverse sectional view of the holder as illustrated in Figure 2 taken on a plane substantially indicated by the line 3—3; Fig. 4 is a fragmentary perspective view similar to a portion of Figure 1 but showing an alternative form of construction; Fig. 5 is a transverse sectional view through the electrode holding zone of the apparatus illustrated in Figure 4.

Referring now more specifically to the drawing and more especially to Figures 1, 2 and 3, the form of electrode holder here illustrated consists of side bars 1 and 2 which are preferably of steel or formed of some other electrically conductive material which also possesses resilient properties. To the rear end of the bars 1 and 2 is secured a handle, generally indicated at 3, of suitable insulating material whereby the tool may be grasped and manipulated by the operator. The bars 1 and 2 may be supported in spaced relation, as most clearly illustrated in Figure 2 and an electrical conductor 4 for the welding current may be secured to such bars in the manner illustrated in this figure.

The forward ends of the bars 1 and 2 are the electrode gripping and supporting jaws and are normally urged toward each other by means of a bolt 5 and a spring 6, the tension of which

may be adjusted by means of a wing-nut 7. A spacer 8 may be positioned between the bars 1 and 2 so as to maintain the bars separated for a short space when no welding pencil is in the holder for the purpose hereinafter more fully explained.

One of the bars such as 2 has a bracket member generally indicated at 9 secured thereto by spot welding or the like, which bracket extends above the bar for an appreciable distance, as most clearly illustrated in Figure 3, and then extends transversely of the bars in the fulcrum member 10. The corners 11 of the bars adjacent the fulcrum member 10 are bent apart, as most clearly illustrated in Figure 1, for the purpose presently to be explained.

When the above described form of holder construction is employed, the electrode pencil, which may be either metallic or non-metallic, is positioned in the holder by simply inserting the end 78 under the fulcrum member 10 and then rotated in a counterclockwise direction, as viewed in Figure 1, until the pencil is forced between the bars 1 and 2. Having the corners 11 of the bars bent outwardly facilitates the entry of the pencil 80 therebetween. The spacer member 8 likewise holding the bars apart for a short distance facilitates the entry of the pencil between the bars as it is rotated about the fulcrum 10. The force with which the bars grip the pencil may be regulated by the adjustment of the wing-nut 7 which adjusts the tension of the spring 6.

Instead of having the fulcrum member 10 formed in the manner illustrated in Figures 1 and 3, I may provide a fulcrum member 12 such as 90 illustrated in Figure 4. The member 12 extends transversely of the bars 1 and 2 but provides a cup-shaped abutment into which cup 13 the end of the pencil may be inserted and then rotated about this fulcrum point to be forced between 95 the bars 1 and 2.

The form of construction illustrated in Figure 1 is primarily adapted to be employed when a carbon or bare metallic electrode is employed and when such is the case, the end of the pencil may be permitted to project upwardly above the abutment member 10. When welding with heavily coated pencils, however, the form of construction illustrated in Figures 4 and 5 is employed.

When a heavily coated weld pencil is employed, such pencil must be gripped at the end for the reason that if the pencil were gripped intermediate its ends, the welding current would be required to pass through this heavy coating which, if this were possible, would undoubtedly 116

destroy the desirable characteristics of such coatings in this local area and for some types of coating which have insulating properties, some of such coating would have to be removed in order to secure a current flow from the holder to the electrode.

By the employment of the form of holder illustrated in Figures 4 and 5, the gripping of the end of the covered electrode is greatly facilitated and the fulcrum member 12 assists in leading the welding current to the bare end of the coated pencil. From the above description it will be apparent that the holder is exceedingly light and accordingly easy to manipulate, may be manufactured at a relatively low cost, and is particularly useful due to the facility with which the electrode may be placed between the gripping jaws.

Other modes of applying the principle of my invention may be employed instead of the one explained, change being made as regards the mechanism herein disclosed, provided the means stated by the following claim or the equivalent of such stated means be employed.

I, therefore, particularly point out and distinctly claim as my invention:

An electrode holder comprising electrode gripping jaws and a fulcrum member adjacent the ends of said jaws provided with a cupped portion adapted to terminally engage an electrode and about which the electrode may be rotated and forced between said jaws.
